PLATE OR SIMILAR ARTICLE

Wataru Uda, 2181 Central Road, Apt. A, Fort Lee, N.J.

Filed Jan. 7, 1964, Ser. No. 78,110

Term of patent 3½ years

(Cl. D44—15)

The figure is a plan view of a plate or similar article showing my new design, a portion of the design being shown between dotted lines and a repeat portion being shown between dot-and-dash lines.

The plate is of a conventional configuration when viewed from side and bottom thereof.

I claim:

The ornamental design for a plate or similar article, substantially as shown and described.
